UNITED STATES PATENT OFFICE.

BASIL H. SAVAGE, OF SAN FRANCISCO, CALIFORNIA.

CARBONATOR.

Application filed February 15, 1928. Serial No. 619,255.

The present invention relates to improvements in carbonators or more generally in means for charging a liquid with the gas under pressure. While the ideas expressed 5 in the present invention are more particularly applied to a carbonator such as is used at the present time in a soda fountain, the invention should not be confined to this particular apparatus and might successfully be 10 used in other combinations as for instance, in connection with the charging of gasoline with air in a carbureter. The principal object of the present invention is to disclose a more perfect means for obtaining a thorough 15 absorption of the gas, in this particular case carbon dioxide by the liquid which in this case would be water. This thorough absorption is brought about by creating a large surface area between the liquid and the gas 20 allowing a large thin layer of gas to be in continuous contact with a large thin layer of liquid. A vessel adapted to be filled with the liquid has means associated therewith for dividing the liquid into a large plurality of 25 single layers and for simultaneously entrapping thin layers of gas above each layer of liquid. Combined with this system of distribution is a feature allowing the supply of gas to be controlled so that when a surplus 30 amount of gas is present the supply is shut off automatically and is not opened until the free gas has been reduced to a predetermined amount due to the absorption of part of the gas by the liquid. Further objects and ad- 35 vantages of my device will appear as the specification proceeds.

The preferred form of my invention is illustrated in the accompanying drawings in which Figure 1 shows a vertical section 40 through my carbonator, Figure 2 a horizontal section through the same taken along line II-II of Figure 1, Figure 3 a detail plan view of a valve controlling device, Figure 4 a section through the same taken along line IV-IV of Figure 3, Figure 5 a detail view of a guide sleeve, Figure 6 a section through the same taken along line VI-VI of Figure 5, Figure 7 a bottom plan view of said sleeve, Figure 8 a vertical section 45 through one of a plurality of bells used in my device, Figure 9 a perspective view of a valve stem, Figure 10 a top plan view of a float supporting member, Figure 11 a central section through the same, Figure 12 a vertical section through a nipple serving as a gas intake port and Figure 13 a sectional view

of a spacing member interposed between two of the valves previously referred to. While I have shown only the preferred form of the invention it should be understood that various changes or modifications may be made within the scope of the claims hereto attached without departing from the spirit of the invention.

The housing (1) for my carbonator rests 65 on a base (2) and comprises an elevated bottom plate (3), a cylindrical wall (4) made preferably of two concentric sheets (6) of metal having heat insulating material such as asbestos between the same as shown at (7) 70 and a ring (8) channel-shaped in cross section lying on top of the wall and engaging the upper ends of the two concentric sheets so as to prevent displacement of the same. The cylindrical housing is covered by means 75 of a suitable lid (9) also preferably filled with insulating material as shown at (11), a knob (12) facilitating the handling of the same.

In this housing is supported concentric 80 with the same a cylinder (13) engaging a groove (14) in the bottom of the housing and a groove (16) in a top plate (17) so as to form a gas tight chamber (18). The upper plate (17) is pressed upon the wall 85 (13) and the latter upon the bottom plate (3) by means of nuts (15) threadedly engaging rods (20) rising from the bottom on the outside of the cylindrical wall (13) and extending through perforations in the 90 upper plate. Water may be admitted into this chamber through a pipe (19) connecting with any suitable source of water, as for instance the city water pipes and provided with a check valve (21) preventing water 95 from flowing backward. A second pipe (22) communicating with the bottom of the chamber (18) serves as a drain pipe.

Gas is admitted from any suitable supply 100 through the pipe (23) by the following arrangement: A sleeve (24) threadedly engages the bottom plate of the housing at its center and extends slightly above the bottom member (3) and through a considerable distance below the latter member. Its lower 105 end which is enlarged in cross section is threaded internally as shown at (26) and is adapted to receive the upper reduced end of a nipple (27) having a nozzle (28) of very small cross sectional area which latter 110 threadedly engages the end of the pipe (23). The sleeve (24) which is shown in detail

in Figures 5, 6 and 7 is adapted to serve as a guide member for the lower end of the stem (29) extending through the length of the chamber and is provided with a plurality of internal grooves (31) allowing the gas to pass the stem provided the latter is raised sufficiently high to clear the nozzle (28). The stem is provided in its lower end with a small body of rubber (32) which closes the nozzle (28) if the stem is pressed downwardly.

The upper end of the stem (29) is guided by means of a sleeve (33) disposed in the center of the top plate and is provided near its top with a collar (34) adapted to be engaged and to be pressed down upon by the short arms (36) of a plurality of levers (37) pivotally supported between lips (38) extending downwardly from a ring (39) formed integrally with the sleeve (33). The long arms (41) of the levers bear on the top surface of a float (42) so that when the float rises the stem (29) is forced downwardly and when the float falls the stem (29) is allowed to rise under the influence of the gas pressure.

The float (42) consists of a large plurality of inverted bells (43), one of which is shown in detail in Figure 8. Each bell consists of a disc (44) having a flange (46) depending from its outer circumference and having a depressed central portion (47) formed by an internal flange (48) and a bottom member (49). The latter has a central perforation (51) and the internal flange (48) is provided with a plurality of perforations (52) disposed in such a manner that they are below the disc (44) but above the lower extremity of the outer flange (46). The perforation (51) allows the bell to slidably engage a tube (53) which latter is made slidably on the stem (29). Between each two bells is interposed a spacing member (54) slidable on the tube and provided at its upper end with an enlarged cup (55) adapted to engage the depressed central portion of the bell above it whereby all the bells are held in parallel relation. The depressed central portion of the lowermost bell rests on a disc (57) provided with a flange (58) encircling said inner portion. This disc threadedly engages the tube (53) and all the bells and the spacing members are forced into one firm unit by means of a nut (60) threadedly engaging the upper end of the tube (53). The disc (57) is supported on the sleeve (24) which as previously stated extends slightly above the bottom plate of the carbonator. To allow gas to pass between the latter disc and the sleeve while the float is in its lowermost position I provide transverse grooves (58) in the latter sleeve as shown in Figures 5 and 6.

Carbonated water may leave the chamber through small passages (59) in the sleeve

(33) so as to enter a tube (61) communicating with said passages through a port (62) in an embossment (63) to which the tube is secured by means of a union (64). The tube (61) leads into the exterior by communicating with a pipe (66) supported in a bracket (67) extending from the top plate (17). Any suitable faucet may be connected to the latter pipe for withdrawing the carbonated water.

The operation of the device may be described as follows: Water is admitted under pressure through the pipe (19) and the pipe (23) is connected to a suitable source of carbon dioxide under pressure. Normally the pressure of the gas exceeds that of the water. When there is neither water nor gas in the chamber (18) the float will descend to its lowermost position as shown in Figure 1. The gas being under pressure will lift the rod (29) sufficiently high to allow the gas to pass the same through the grooves (31) in the sleeve (24) at the same time the water rushes into the chamber. Both water and gas will first fill the lowermost bell, the gas rising and occupying the upper space while the water will occupy the lower space. A thin layer of gas will be entrapped in the valve while a surplus amount will follow the course of the water and rise with the same through the holes (52) to fill the space of the next bell. In a similar manner one bell will be filled after the other and a thin layer of gas will be trapped in each bell so as to engage a large area of water which will cause the gas to be readily absorbed by the water. The buoyant effect of the water on the gas entrapped under the bells causes the float to rise and lifts the long arms (41) of the levers (37) thereby depressing the collar (34) on the stem (29) and forcing the latter downwardly whereby the nozzle (28) is closed. Thereby the supply of gas is shut off and the valve for the gas supply is not opened until the gas entrapped under the bells is absorbed by the water. It will be seen that in this manner a thorough absorption of the gas by the water is obtained and that at the same time the gas supply regulates itself automatically in accordance with predetermined rules.

I claim:—

1. In means for charging a liquid with a gas, a chamber, means for admitting the liquid into the same, means for admitting the gas into the chamber and a float control for the gas including a plurality of inverted bells mounted above one another in spaced relation, each being adapted to trap a layer of gas, and having a downwardly extending central flange with an outlet therein disposed intermediately of the top of the bell and the lower extremity of the bell, said outlet being adapted to allow a surplus of gas to escape into the next higher bell.

2. In means for charging a liquid with a gas, a chamber, means for admitting the liquid into the same, a central gas intake in the bottom, a vertical stem adapted to close the gas intake and a float slidable on the stem having means associated therewith for depressing the stem so as to close the gas intake when the float rises, the float comprising a plurality of bells arranged above one another in spaced relation adapted to trap layers of gas within the liquid.
- 5 10 15 20
3. In means for charging a liquid with a gas, a chamber, means for admitting the liquid into the same, a central gas intake in the bottom, a vertical stem adapted to close the gas intake and a float slidable on the stem having means associated therewith for depressing the stem so as to close the gas intake when the float rises, the float comprising a plurality of bells arranged above
- one another in spaced relation adapted to trap layers of gas within the liquid, and having a downwardly extending central flange with an outlet therein disposed intermediate of the top member and the lower extremity of the bell, said outlet being adapted to allow a surplus of gas to escape into the next higher bell.
- 25
4. In means for charging a liquid with a gas, a chamber, means allowing the liquid and the gas to enter the chamber through the bottom thereof with the pressure of the gas exceeding that of the water, a valve for limiting the admission of the gas and a float controlling the valve formed to separate the water and the gas in successive layers in the chamber for securing a better absorption of the gas.
